UNITED STATES PATENT OFFICE.

ARTHUR SYDNEY McCLEAVE, OF MONTREAL, QUEBEC, CANADA, ASSIGNOR OF ONE-HALF TO JOSEPH ALBERT DESNOYERS, OF MONTREAL, CANADA.

FURNACE-DOOR STRUCTURE.

Application filed April 5, 1926. Serial No. 99,833.

The invention relates to a furnace door structure as described in the present specification and illustrated in the accompanying drawings that form part of the same.

- 5 The invention consists essentially of the novel features of construction pointed out broadly and specifically in the claims for novelty following a description in detail of an acceptable form of the invention.
- 10 The objects of the invention are to promote the combustion of the fuel and particularly maintain the newly fed fuel in an active state of disintegration and thereby avoid the release of gases in their primary and 15 non-heating stages; to insure a constant and ready flow of air and at the same time eliminate any dampening effect due to low temperatures; to produce a device of the kind herein described at a low cost and universally applicable with minor changes for the 20 different installations; to facilitate the operations of the stoker and keep a steady pressure of steam in the generation of the same and in other uses maintain an even temper- 25 ature; to accompany the features illustrated and described in the drawings and description attached to an application for a patent Serial No. 64,172, filed October 22, 1925, by separately protected elements that may or 30 may not be used apart therefrom; and generally to provide a useful efficient and economical furnace door structure.

In the drawings, Figure 1 is a longitudinal sectional view of the air director and 35 inside elevation of the air distributor showing the furnace front and door broken away and in vertical section.

Figure 2 is a sectional plan view of the air director.

40 Figure 3 is a detail of an air distributor showing the inner slotted wall.

Figure 4 is a detail of an air distributor showing the outer wall and connections to the inlet.

45 Figure 5 is an upper plan view of the extended sill forming the upper wall of the air director and the distributors alongside.

Figure 6 is a reduced perspective view of the complete structure.

50 Like numerals of reference indicate corresponding parts in the various figures.

Referring to the drawings, the extended sill 10 projects inwardly through the furnace front 11 for the greater portion of its 55 length and is supported on the dead plate 12

and therewith forms the air director chamber 13 forming the passage from the inlet 14 to air distributors 15 and 16 on either side, the said sill 10 being here shown as flaring outwardly, though the shape is entirely a 60 matter of installation.

The air passage through the chamber 11 is made tortuous by means of the long baffles 17 and short baffles 18, the long baffles terminating short of the side walls to leave the passages 19 and 20 and the short baffles extending from the side walls to leave the central passages 21, thereby deflecting the air for heating purposes until it reaches the end baffles 22 and 23, where it passes through 70 the central passage 24 and is deflected by the blank end wall 25 beyond the outturned flanges 26 and 27 to the air distributors 15 and 16 having the inlets 28 and 29 widened to the fullest extent possible by the back-turned sections 30 and 31 of the end baffles 22 and 23 and upturned portions 32 and 33 of the sill 10.

The air distributors 15 and 16 have the 80 outlet slots 34 and outlet holes 35 through the inner walls at the highest and inner ends of said distributors for they taper to the flanges 36, which are bolted to the lugs 37 from the side walls of the sill 10 within the furnace front 11.

The sill 10 extends outwardly beyond the furnace front 11 and the nuts 38 engage said front on the inner side and the bolts 39 carrying said nuts 38 project outwardly 90 from the sill lugs 38^a through the fuel opening in the front 11 into the door frame 40.

The sill 10 is formed into a recess 41 at the extreme outer end to receive the panel door 42, which runs behind the angle bars 43 and 44 secured to the door frame 40. 95 The sill 10 is flanged downwardly at 45 at the extreme outer end and behind this flange the air inlet 46 leads into the air chamber 13 the flow of air therethrough being controlled by the segmental damper 47 fixedly mounted on the shaft 48, which is journalled in the side walls of sill 10 outside the furnace front, said side walls being slotted at 49 for said furnace front.

The panel door 42 is here shown as operated by the sprockets 50 mounted on the shaft 51 journalled in the bearings 52 from the door frame 40.

The shaft 51 is driven by the gear 53, 110 which in turn is driven by the segmental

gear 54 rotated by the chain and sprocket mechanism 55. The mechanism 55 is operated by the gears 56 actuated by the pedal 57 to open the door 42 while the weight 58 returns the mechanism to its starting position and the spring 59 pulling on the chain 60 mounted on the pulley 61 assists in closing the door. This operating mechanism is more particularly described in the copending 10 application Serial No. 64,172 filed October 22, 1925, and is only mentioned herein as the preferable means for coacting with the novel features set forth in detail hereinbefore.

15 In the operation of this device, the panel or slot door is opened and closed by means of the foot lever, but this part of the mechanism is not specifically a feature of this invention.

20 However the feeding of fresh fuel naturally needs draft from below rather than the dampening effect of the air from above, therefore the indrawn air to the air distributors is lessened or cut off entirely by the 25 rotating damper described.

The moment the flame springs from the fuel the top air is increased and follows the tortuous path in the air chamber and becomes heated and flows into the air distributors on either side and from there escapes through the outlets to mix with the carbon gases rising from the fuel to effect good combustion and the resultant heating gases.

25 The assembly of the parts in this invention is essential in its details and is very important in relation to the particular form of door, as it is of one structure therewith and

in the installation the furnace front remains practically untouched, yet the fastening thereto is so rigid, that to all intents and 40 purposes it is integral therewith. The simplicity of the structure must be emphasized for every part is carried by the door frame both inside and out and all that is necessary for cooperation is the permanent dead plate 45 of the furnace with the door sill to complete the air chamber and the furnace front with the door frame to support all the parts, therefore the device is a unit in furnace construction and applicable with minor 50 changes to many types of furnaces.

What I claim is:—

In a furnace door structure, a door frame having an air inlet passage thereacross from the underside, a valve adapted to close said 55 passage and suitably operated, an air director formed of flaring side distributing boxes having wide inlet openings and end outlet openings through the inner walls, a sill sloping downwardly from the door frame and 60 joined to said boxes and upwardly turned to include said wide inlet openings, central inner enclosure forming the air passage from the frame inlet and having baffle walls deflecting the air in its flow through a central 65 inner opening to the main chamber under the sill and communicating with the aforesaid distributing boxes and said enclosure having contiguous lugs and bolts securing 70 them together.

Signed at Montreal, Canada, this 17th day of March, 1926.

ARTHUR SYDNEY McCLEAVE.
